(57) **ABSTRACT**

A clutchable pry bar includes a bar member with a fitting connector; a rack member fitted with the fitting connector of the bar member, including two slots adjacent to a closed end of the rack member, and including two through holes proximate to an opened end of the rack member; a ratchet shaft inserted to the through hole of the rack member, and including a first end portion disposed on one end thereof; at least one ratchet member fitted to the ratchet shaft, a plate member movably fixed to the slots of the rack member, a returning spring between pegs of the plate member and a central extension of the bar member; a stem member to be retained with the ratchet shaft after the stem member is inserted to a radial bore of the ratchet shaft.

response to the cutouts 2210 of the slots 221 so as to be inserted through the cutouts 2210 of the slots 221 to be retained on the two inner walls of the two sides of the rack members 22, such that the plate member 27 is positioned in the slots 221;

a returning spring 28 between the pegs 271 of the plate member 27 and the central extension 211 of the bar member 21 so that the plate member 27 moves between the slots 221 of the rack member 22;

a stem member 29 including a large-diameter segment 290 inserted through the radial bore 230 of the ratchet shaft 23, and including at least one ball 291 mounted thereon to retain the stem member 29 with the ratchet shaft 23 after the stem member 29 is inserted to the radial bore 230 of the ratchet shaft 23.

In assembly, as shown in FIGS. 6 and 7, the bar member 21 is rotated to actuate the rack member 22 to rotate toward a predetermined direction, and the ratchet shaft 23 abuts against the ratchet member 25 by using the toothed recesses 251 and the plate member 27 so as to prevent the toothed recesses 251 which rotate from a deep-to-shallow direction from rotating idly when the returning spring 28 retracts inward, and when the toothed recesses 251 rotate from a shallow-to-deep direction, the plate member 27 engages with the toothed recesses 251 so that the ratchet member 25 rotates with the ratchet shaft 23. In operation, the stem member 29 is inserted to an axial mouth of a head member of a winch to be retained by ways of the balls 291, hence when the ratchet member 25 and the plate member 27 rotate in a retaining direction, the stem member 29 is actuated to rotate so that the ratchet shaft 23 actuates the head member of the winch by means of the stem member 29. Furthermore, when the ratchet member 25 and the plate member 27 rotate in an idly rotating direction, the stem member 29 can not actuate the head member of the winch so that the pry bar allows to be operated reciprocately on the head member of the winch to pull a belt of the head member tightly, quickly, and effortlessly.

While we have shown and described various embodiments in accordance with the present invention, it is clear to those skilled in the art that further embodiments may be made without departing from the scope of the present invention.

What is claimed is:

1. A clutchable pry bar comprising:

a bar member;

a rack member formed in a U shape to be fitted with a fitting connector of the bar member, including two slots arranged on two sides thereof individually adjacent to a closed end of the rack member, and including two through holes defined on the two sides thereof respectively proximate to an opened end of the rack member; a ratchet shaft inserted to the two through holes of the rack member; and including a first end portion with a radial bore disposed on one end thereof;

a locking member for locking the ratchet shaft to another side of the rack member;

at least one ratchet member fitted to the ratchet shaft, wherein the ratchet member includes a plurality of toothed recesses arranged around an outer periphery thereof;

5 a plate member movably, fixed to the two slots of the rack member, including a toothed block to engage with the ratchet members, and including a number of pegs extending outward from the toothed block relative to the closed end of the rack member;

a returning spring between the pegs of the plate member and a central extension of the bar member so that the plate member moves between the two slots of the rack member;

a stem member, including a large-diameter segment, inserted through the radial bore of the ratchet shaft, and including at least one ball mounted thereon to retain the stem member with the ratchet shaft after the stem member is inserted to the radial bore of the ratchet shaft.

10 2. The clutchable pry bar as claimed in claim 1, wherein the bar member includes a fitting connector fitted on one end thereof.

20 3. The clutchable pry bar as claimed in claim 2, wherein, the fitting connector includes a central extension disposed on a top end surface thereof.

25 4. The clutchable pry bar as claimed in claim 1, wherein the rack member includes an opening defined on the closed end thereof, and each slot includes a cutout formed thereabove.

30 5. The clutchable pry bar as claimed in claim 1, wherein the ratchet shaft includes a stopping shoulder connected with the first end portion and extending radially from an outer rim thereof, and includes a second end portion mounted on another end thereof to be inserted to the holes of the rack member, such that the first end portion of the ratchet shaft is limited outside the rack member by using the stopping shoulder, and the second end portion includes two opposite tangent planes fixed thereon individually, and includes an aperture formed therein.

35 6. The clutchable pry bar as claimed in claim 1, wherein the locking member includes a lock ring and a bolt.

40 7. The clutchable pry bar as claimed in claim 1, wherein the ratchet member includes a central orifice defined thereon and corresponding to two opposite tangent planes of the rack member.

45 8. The clutchable pry bar as claimed in claim 1, wherein the plate member includes two bosses mounted on a top surface of the toothed block and corresponding to the cutouts of the slots.

50 9. The clutchable pry bar as claimed in claim 8, wherein the bosses are inserted through the cutouts of the slots to be retained on two inner walls of the two sides of the rack members, such that the plate member is positioned in the slots.
